UNITED STATES PATENT OFFICE

MARIO BELLINGERI, OF MONZA, ITALY

CREEL FOR WINDING WARP BEAMS

Application filed January 24, 1927, Serial No. 163,174, and in Italy January 28, 1926.

The subject of the present application for a patent is a continuous supply creel for winding warp beams in variable combinations, illustrated, by way of example, in the 5 accompanying drawings, in which:—

Figure 1 is a perspective view of a compartmental column comprised in the invention.

Figures 2 and 3 show, respectively, a perspective view and a side view of a carrier 10 holding tray.

Figure 4 is a perspective view of a carrier.

Figure 5 is a detail view of a thread distributor.

Figures 6 and 7 are sections on the lines 15 VI—VI and VII—VII of Figure 5 respectively.

Figure 8 is a section on the line VIII—VIII of Figure 14 showing two carriers 20 placed side by side.

Figures 9 and 10 show respectively a front view and a vertical section of a detector device.

Figures 11 and 12 are diagrams illustrating the distribution of threads drawn out of 25 a series of columns.

Figure 13 shows diagrammatically a set of columns with the collecting and tensioning rollers.

Figure 14 is an isometric view of the columns, distributors and detector.

The creel forming the subject of this invention dispenses with successive stages preliminary to the winding of the warp beam.

35 The said continuous supply creel is composed substantially of columns of thread carriers combined to form sets supplying groups of warp ends of varying quantities. The latter are preferably kept apart by pins or lease rods which determine the spacing of each group, the various groups being afterwards brought together on suitably arranged horizontal rollers which impart a uniform tension to the completed warp.

45 Before being wound on the warp beam, the threads pass between pins or lease rods, which determine the spacing between the groups, so that they can be arranged laterally in position corresponding with the draft 50 of the warp and enable the component

threads to be arranged in a varying manner, which cannot be obtained by the existing method of working, in which the draft is fixed beforehand.

As shown in the drawing, the column 1 is 55 divided into several compartments, each of which contains several metal trays 2, with central partitions 3, and each holding two carriers 4 which in turn contain three bobbins 5. These carriers, which are of sheet metal, the sides being folded over at the bottom and one end being open, hold the bobbins 5, the axes of which converge towards the unwinding point, which is situated in the plane of the partition 3. There is always one carrier 60 operative, the other being in reserve and brought into operation when the bobbin in the first one has run out. At one end of the partition 3 there is a support 6 on which rests the connecting thread running from the head 65 of one bobbin to the base of the other and enabling the thread, when the first carrier has become empty, to pass over the partition 3 and bring the second reserve carrier into 70 operation.

The thread issuing from the carrier passes 75 to a detector composed of a vertical bracket 7 positioned on the column 1 adjacent the inner ends of the trays 2 into the interior of which extends a metal spiral 8 connected to a movable oscillating weight 9 carrying a finger 10 adapted to engage a hook 11 pivoting on the said spiral 8. To one side of the spiral 8 and on the bracket 7 is secured a spiral hook 12, whilst on the opposite side 80 is arranged a contact strip 13 attached to a conducting wire 14. A conducting wire 15 is connected to the spiral 8. Ordinarily, the thread passes through the spiral 8, lifts the hook 11 and passes through the hook 12, so that the hook 11, being drawn away from the strip 13 ordinarily breaks the electric circuit (for example comprising a lamp, not shown,) and remains out of contact with the finger 10, which is out of action so long as 85 the thread is unwinding from the greater diameter of the bobbin. When the thread is unwinding from the lesser diameter of the bobbin, and is thus subjected to greater tension, the hook 11 is drawn further outwards 90 95 100

by the traction of the thread, and the weight 9 attached to the finger 10 is brought into action by said finger. When the thread is again unwinding from the greater diameter of the bobbin, the weight 9 restores the hook 11 to its original position, and consequently the thread is kept in constant tension.

In the event of the thread breaking or being overstrained, the hook 11 rises to the level of the hook 12 and releases the thread, with the result that the weight 9 brings it into contact with the strip 13, thus completing the electric circuit, the rupture or overstraining of the thread being then revealed by the lighting of the detector lamp.

The thread issuing from the hook 12 of the detector device passes to a distributor 40 (Figure 5) composed of the vertical bars 14, 15, 16 and the horizontal bars 17, 18, 19, 20 pivotally connected to the vertical bars, so that the bars can be brought closer together or moved apart whilst still remaining parallel. The threads from the first compartment of a column are carried over the pins or hooks 21 of the horizontal bar 17 and, passing under the bar 18, are carried round the hooks 22 of the bar 19, and finally, after passing to the bar 20, remain separated, and pass on to a roller 23. The threads from the second compartment engage the pins 24 of the bar 18 and then, passing between the pins or hooks 22, of the bar 19 pass between the pins or hooks 25 on the arm 20, and like the former are led to the roller 23, whilst the threads from the third and fourth compartments are arranged above those from the 1st and 2nd compartments and follow the lines indicated in Figure 5 to the corresponding roller 23.

By altering the inclination of the arms 17-20 constituting the distributor, the threads carried by said arms can be brought closer together, so as to vary the number of warp ends per unit of count. Assuming, for purposes of demonstration only, the number of threads in a compartment to be 10, then, if the arms of the distributor are arranged horizontally and are 40 centimetres in length, there will be a thread every 4 cm., whereas, retaining the 10 threads and inclining the arms at an angle of 45°, there will be a thread at every 2 cm., that is to say, two threads per 4 cm. It follows, therefore, that the spacing is variable in relation to the length of the arms and the number of threads, and depends on the greater or smaller angle of inclination of the arms of the distributor.

By combining the columns of carriers into sets and arranging these in parallel lines at suitable intervals, an indefinite aggregation of threads can be obtained, which can be subdivided by the removal or substitution of columns and groups so as to maintain a constant relation between the number of groups removed and substituted and the total num-

ber of the groups. Moreover the control of the operations proceeding interiorly between one line and the other is quite distinct from the feeding of the carriers, which is effected from outside the line, thus presenting an advantage in the organization of the work. Thus an infinite series of warp drafts can be obtained and with a metric length which cannot be obtained at present, because the draft has to be settled in each case, unless the draft is in series, because the winding of the warp as a whole on a single beam does not allow lateral shifting of the threads which, being laid side by side from the beginning, cannot be separated.

It will be understood that the details of shape, construction, structure, dimensions, application, finish, assembling arrangement, or the like, may be varied according to circumstances without departing from the scope of the invention, set forth in the claims hereunto annexed, as may be found more suitable and better adapted to conditions of practice.

I claim:

1. A creel comprising a plurality of compartmental columns, removable trays in the columns, a plurality of thread bobbins in each tray, a distributor for each column adapted to space the threads from the bobbins and consisting of vertical bars, horizontal bars pivoted to the vertical bars so that they may be moved in parallel relationship, and thread guiding pins on the horizontal bars.

2. A creel comprising a plurality of pairs of compartmental columns, the columns in each pair facing each other, thread carriers in the compartments of each column, a distributor for each column adapted to space the threads issuing therefrom and means for adjusting the spacing of the threads, said means comprising thread bars pivotally connected to a plurality of vertically disposed bars, one of which is rigidly affixed to said compartmental columns.

MARIO BELLINGERI.
